TRACTION MECHANISM

Original Filed Oct. 8, 1921

UNITED STATES PATENT OFFICE

ROBERT C. OSGOOD, OF CLAREMONT, NEW HAMPSHIRE, ASSIGNOR TO SULLIVAN MACHINERY COMPANY, A CORPORATION OF MASSACHUSETTS

TRACTION MECHANISM

Application filed October 8, 1921, Serial No. 506,325. Renewed January 30, 1930.

My invention relates to hoisting mechanisms, and more particularly to hoisting mechanisms of a portable double drum type.

An object of my invention is to provide an improved hoisting mechanism. Another object of my invention is to provide an improved hoisting mechanism of the double drum type. A further object of my invention is to provide an improved hoisting mechanism of the double drum type in which a single motor may cooperate alternately with the drums of said hoist to effect rotation thereof. Other objects and advantages of my improved mechanism will be hereinafter apparent.

In the accompanying drawing I have shown for purposes of illustration one form which my invention may assume in practice.

In this drawing,—

20 The view is one mainly in central vertical longitudinal section through my improved hoisting mechanism, but having parts shown in elevation.

In the form of my invention which I have shown herein for purposes of illustration, I provide a main base 1 having upstanding standards 2 and 3 at the opposite ends thereof and in these standards I journal stub shafts 4, of which but one is shown, constituting the 30 supports for the remote ends of the drums 5 and 6. Intermediate the drums 5 and 6 is arranged a stationary housing 7 which has a hollow interior 8 in which a motor generally indicated 9 is arranged and which also contains a clutch chamber 10, hereinafter more fully described. The motor 9 comprises a pair of intermeshing rotors 11 and 12 provided with intermeshing tooth blades 13 cooperating upon rotation of the rotors to form 40 expanding pockets in a manner more fully set forth in the copending application of one Morris P. Holmes, Serial No. 255,797, filed September 26, 1918, now Patent No. 1,520,242, granted Dec. 23, 1924, the motor per se 45 not being my invention, but that of the said Holmes.

The rotor 12 is provided with a shaft 14 upon which is secured a pinion 15 and the latter meshes with a gear 16 mounted upon a 50 shaft 19 which is journaled in a bearing 17

in one head of the motor 9 and in a second bearing in one head, 18, of the casing 7. A pinion 20 is also secured to the shaft 19 and is rotatable with the gear 16 and serves, by reason of its mesh with a gear 21, to rotate the same in a bearing 22 for the latter formed on the head 18. A gear 23 is arranged in intermeshing relationship with the gear 21 and is disposed mainly within the clutch housing 10 previously referred to. This gear, which has a wide face, is splined to a sleeve 24 which is rotatable upon a shaft 25, on one of whose ends a pinion 26 is integrally formed or otherwise rigidly secured. Keyed to the shaft 25 is a clutch member 27 held against longitudinal movement relative to the shaft and having teeth 28 adapted to be engaged by clutch teeth 29 formed on one end of the sleeve 24. A shifter 30 is arranged to cause the teeth 29 to engage with and to be freed from the teeth 28. Rotatable relative to the shaft 25, in a bearing in the end of the casing 10, is a second sleeve 31 having a pinion 32 formed thereon and provided with clutch teeth 33 adapted to be engaged by teeth 34 formed on the pinion 23. It will thus be evident that by longitudinal movement of the sleeve 24 the shaft 25 may be positively driven, causing rotation of the pinion 26, or the sleeve 31 may be rotated causing rotation of the pinion 32.

The drums 5 and 6 are respectively provided at their adjacent ends with internal gears 36 and 35 with which the pinions 26 and 32 are in constant mesh. The adjacent ends of the drums 5 and 6 are journaled upon projecting stub shafts 37 and 38 secured to the ends of the central casing member 7. The drums 5 and 6 are each provided with braking means respectively designated 39 and 40 and as best shown at the left hand side of drum 5, comprising peripheral braking surfaces 41 on the drum arranged to cooperate with brake bands 42 held against rotation relative to the frame 1 by means 43 and applicable frictionally to the braking surfaces 41 by manual control means 44. Fluid pressure to cause operation of the motor 9 is supplied by way of pipe 45, and motive fluid after it has operated in the rotors may be exhausted

through openings, not shown, in the ends of the motor housing.

The mode of operation of this mechanism will be readily apparent. Assume that the motor 9 is in operation and that the pinion 15 is being rotated in a counterclockwise direction (viewed from the right hand end of the hoisting mechanism). By reason of the pinions 16 and 20 the pinion 21 will likewise be caused to rotate in a counterclockwise direction and will rotate the pinion 23, which is, as will be evident, capable of a sliding movement without running out of mesh with the pinion 21, in a clockwise direction. Now by moving the sleeve 24 toward the left, the clutch teeth 29 will be caused to engage the teeth 28 and the shaft 25 will be rotated, causing the pinion 26 to drive the internal gear 36 in a clockwise direction. Accordingly, the flexible member 51 wound counterclockwise on the drum 5 will be wound in. It will be understood that during this time the drum 6 may be either permitted to rotate freely, if there is a pull on the rope 52, by releasing the braking mechanism 40, or may be held stationary. If now the sleeve 24 be shifted toward the right, the teeth 34 will engage the teeth 33 and drive the pinion 32. Then the drum 6, by reason of the intermesh of the teeth of the gears 32 and 35, will be caused to rotate in a clockwise direction and the cable 52 which is wound in a counterclockwise direction will be wound in, it being evident that the drum 5 may be free to rotate or held stationary during this operation by slackening or tightening its respective brake band 42. In view of this explanation various further possible modes of operation and uses of this hoisting mechanism will present themselves to one skilled in the art and accordingly do not need detailed description.

While I have in this application specifically described one form which my invention may assume in practice, it will be understood that this form of the same is shown for purposes of illustration and that the invention may be modified and embodied in various other forms without departing from its spirit or the scope of the appended claims.

50 What I claim as new and desire to secure by Letters Patent is:

1. In a hoisting mechanism, a stationary motor, a pair of relatively rotatable winding drums so disposed that said motor lies between and rotatably supports them, and speed reducing gearing between said motor and drums including a gear common to the driving of both drums, and means for connecting said motor only alternatively to homologous elements of the speed reducing gearings of the different drums.

2. In a hoisting mechanism, a stationary motor, rotatable drums arranged one at each end of said motor, a driving gear carried by each of said drums, a shaft having a gear

fixed thereon meshing with one of said driving gears and a gear loose thereon meshing with the other of said driving gears, and means driven by said motor and selectively connectible with said shaft or with said loose gear.

3. In a hoisting mechanism, a stationary motor, rotatable drums arranged one at each end of said motor, a driving gear carried by each of said drums, a shaft having a gear fixed thereon meshing with one of said driving gears and a gear loose thereon meshing with the other of said driving gears, and means including a sleeve rotatable on said shaft and driven by said motor selectively connectible with said shaft or with said loose gear.

4. In a hoisting mechanism, a stationary motor, rotatable drums arranged one at each end of said motor, a driving gear carried by each of said drums, a shaft having a gear fixed thereon meshing with one of said driving gears and a gear loose thereon meshing with the other of said driving gears, and means including a sleeve rotatable on said shaft and driven by said motor selectively connectible with said shaft or with said loose gear, said shaft, said loose gear, and said sleeve having clutch teeth formed thereon and adapted to connect either of said first two elements with the last.

5. In a hoisting mechanism, a stationary motor housing having parallel rotor chambers therein, cooperating rotors in said chambers, drums rotatable about axes parallel to the axes of said rotors and rotatably supported by opposite ends of said housing, and reducing gearing disposed within said housing and comprising a plurality of intermeshing elements which transmit power to the drums transversely of the drum axes, the axes of rotation of said rotors, said drums and said reducing gearing elements lying in a single plane.

6. In a hoisting mechanism, a motor having a stationary casing, a drum disposed at each end thereof, said casing providing journal means for each of said drums, a driving connection between said motor and drums including a gear disposed between the ends of said motor casing, a shaft extending longitudinally of said motor on the outside thereof and carrying a gear meshing with said other gear, and directly cooperating gears carried by said drums and said shaft.

7. In a hoisting mechanism, a motor, a pair of relatively rotatable winding drums one arranged at each end of said motor, a driving gear carried by each of said drums, a shaft having a gear fixed thereon meshing with one of said driving gears, a gear loose on said shaft meshing with the other of said driving gears, and means driven by said motor and alternatively connectible with said shaft and with said loose gear.

8. In a hoisting mechanism, a motor, a pair of relatively rotatable winding drums one arranged at each end of said motor, a driving gear carried by each of said drums, a shaft having a gear fixed thereon meshing with 5 one of said driving gears, a gear loose on said shaft meshing with the other of said driving gears, and means including a sleeve rotatable on said shaft and driven by said motor alternatively connectible with said shaft and with 10 said loose gear.

9. In a hoisting mechanism, a pair of relatively rotatable coaxial winding drums, a stationary motor intermediate said drums and 15 rotatably supporting the same, driving gearing between one end of said motor and said drums including only constantly meshing gears, and means disposed between the adjacent ends of said drums and slidable longitudinally with reference to the axes of said 20 drums for only alternatively connecting said motor in driving relation with said drums.

10. In a hoisting mechanism, a pair of relatively rotatable winding drums arranged 25 coaxially with each other, a stationary motor between said drums and rotatably supporting the same, and driving connections between said motor and drums including a shaft common to each of said drums, said shaft being disposed parallel to said motor and having means slidable longitudinally with reference to the axes of said drums for only alternatively connecting the motor in driving relation with said drums.

35 11. In a hoisting mechanism, a pair of relatively rotatable coaxial winding drums, a stationary motor aligned with and disposed between said drums and rotatably supporting the same, and means for driving said 40 drums from one end of said motor comprising reduction gearing driven from one end of said motor, said gearing being in mesh at all times and driving control means for mechanically connecting or disconnecting 45 said motor in driving relation to either of said drums.

12. In a hoisting mechanism, a casing having a motor disposed therein and an end chamber, a pair of relatively rotatable winding drums rotatably supported by said casing and driving connections between said 50 motor and said drums comprising an inner set of gears disposed in said chamber and an outer set of gears disposed outside of said 55 chamber, the inner and outer sets of gears being connected to each other by a meshing action between a gear of each set.

13. A mechanism as set forth in claim 11 having a common clutch member controlling 60 the driving connections between the motor and both drums.

14. In a hoisting mechanism, a stationary casing housing a motor, said motor having a motor pinion, a pair of relatively rotatable coaxial winding drums one disposed at an

end of said casing and rotatably supported thereby, each of said drums carrying a gear, a shaft extending longitudinally of said casing parallel with the drum axes and carrying a pinion meshing with one of said drum gears, a pinion coaxial with said shaft and rotatable relative thereto and meshing with the other drum gear, and power transmission connections including gearing connecting said motor pinion with said other pinions. 70

15. In a hoisting mechanism, a stationary motor, rotatable drums arranged one at each end of said motor, driving gears carried one by each of said drums, coaxial driving pinions constantly meshing respectively with said driving gears, a gear driven by said motor disposed intermediate and coaxial with said pinions, and means for connecting said driving gear alternatively to said pinions to drive the latter. 75

16. In a hoisting mechanism, a stationary motor, a pair of relatively rotatable winding drums between which said motor is disposed and for each of which said motor provides a bearing, and speed reducing gearing between 80 said motor and drums including a gear common to drive of both drums, and means for connecting said gear only alternatively to homologous elements of the speed reducing 85 gearings of the different drums. 90

17. In a hoisting mechanism, a pair of relatively rotatable winding drums arranged coaxially with each other, a stationary motor between said drums and rotatably supporting the same, and driving connections between 100 said motor and drums including a shaft common to each of said drums, said shaft being disposed parallel to said motor and having means slidable longitudinally with reference thereto and to the axes of said drums for only 105 alternatively connecting the motor in driving relation with said drums.

In testimony whereof I affix my signature.
ROBERT C. OSGOOD.
